UNITED STATES PATENT OFFICE.

WILLIAM A. WIEDEBUSCH, OF FAIRMONT, WEST VIRGINIA.

HOT-WATER OR STEAM HEATER.

1,024,660.

Specification of Letters Patent. Patented Apr. 30, 1912.

Application filed March 20, 1911. Serial No. 615,513.

To all whom it may concern:

Be it known that I, WILLIAM A. WIEDEBUSCH, a citizen of the United States, residing at Fairmont, county of Marion, State of 5 West Virginia, have invented certain new and useful Improvements in Hot-Water or Steam Heaters, of which the following is a specification, reference being had therein to the accompanying drawing.

10 This invention relates to certain new and useful improvements in heaters for hot water circulating systems, or for generating steam for steam heating systems, the object being to provide a heater which is especially 15 constructed for the use of natural gas as a fuel.

Another object of the invention is to provide a heater which is formed of a plurality of sections so united that the capacity of the 20 heater can be increased or decreased by adding or removing sections.

A still further object of the invention is to provide a water section with corrugated side walls forming a plurality of staggered 25 arranged oval shaped projections which decrease in size from the bottom upwardly in order to decrease the radiating surface of the heating units from the point of admission of the water to be heated to the point 30 of discharge.

A further object of the invention is to provide the water sections exactly alike in order to allow the projections to register with each other when the sections are assembled, forming zigzag passages for the 35 heat units so that the heat will be absorbed by the water within the sections.

Another object of the invention is to provide a header for connecting the supply and 40 discharge pipes to the respective sections which is so constructed that an additional header can be readily connected thereto when the size of the heater is increased by adding other sections.

45 Other and further objects and advantages of the invention will be hereinafter set forth and the novel features thereof defined by the appended claims.

In the drawings—Figure 1 is a front elevation of a water heater constructed in accordance with my invention partly in section; Fig. 2 is a side elevation partly broken away to show the arrangement of the projections formed on the sides of the sections; 50 Fig. 3 is a section taken on line 3—3 of Fig. 2 showing the header in top plan view; Fig.

4 is a vertical section through one of the sections; Fig. 5 is a horizontal section through one of the water sections; and Fig. 6 is a vertical section through one of the water sections especially constructed for generating steam having a dome at its top. 60

Like numerals of reference refer to like parts in the several figures of the drawings.

In the drawings, 1 indicates a heater 65 which is formed of a plurality of water sections 2, each section being mounted upon a base section 3 and in the drawings, I have shown a heater formed of four water sections having a corresponding number of base 70 sections, but it is of course understood that the heater can be formed of one or more water sections. Arranged on the top of the water sections 2 is a smoke box 4 formed of a corresponding number of sections bolted 75 together and the two central sections have semi-circular flanges 5 forming a collar to which a pipe is adapted to be connected leading to a suitable flue, not shown, for conveying the smoke from the heater to the open 80 air. The base sections are also bolted together and are formed hollow, as clearly shown, each section being provided with an opening 6 and a funnel shaped air pipe 7 at its front end into which extends a gas 85 pipe 8 leading from a valve casing 9 to which is connected a supply pipe 10.

The sections 2 are formed exactly alike and a description of one will be sufficient for all, each section comprising a rectangular 90 hollow body having its side walls corrugated to form a plurality of staggered oval shaped projections 11 which decrease in size from the bottom upwardly in order to decrease the radiating surface of the heat units, as 95 the water within said members becomes heated.

Each of the water sections 2 is provided with an inlet boss 12 and an outlet boss 13 which are connected to headers 14 and 15 100 by push nipples 16 of the ordinary construction, said headers having supply and discharge pipes 17 and 18 connected respectively thereto through which the water to be heated is delivered into the water sections and discharged therefrom to the heating system. The ends of the headers 14 and 15 are provided with threaded plugs 19 in order to allow an additional header to be connected thereto when the number of sections is increased to form a heating system of larger capacity. The water passing 105 110

through the push nipples 16 into the lower ends of the water sections 2 is subjected to the greatest amount of heat at the entrance and passes upwardly in a thin column in order that it may be quickly heated when passing through the sections. The corrugations or projections terminate short of the front and rear edges of the sections forming a water space the full width of each section in order to allow a downward circulation of the water. The sections are arranged against each other in such a manner that the projections register as clearly shown in Fig. 1 and the meeting edges are cemented as shown at 20 and the front and rear edges forming the front and back walls of the radiator in use are preferably covered with a heat insulating material, not shown. The sides of the outer sections are inclosed by casing 21 secured thereon by any suitable means in such a manner that they may be readily detached, if desired, to allow an additional section to be added or removed.

25 Arranged within each of the base sections 3 is a burner 22 which is connected at its forward end to the air pipe 8 and comprises a tubular portion 23 into which the air and gas is mixed.

30 In Fig. 7, I show a section 31 especially constructed to be used in connection with a steam heating system and it will be seen that this section is substantially the same as the water heating sections with the exception of the steam dome 32 formed at the top of the same in which the steam accumulates and it will be seen that by simply installing sections of this character on bases as previously described, a steam generating 40 boiler will be formed instead of a hot water boiler.

Having described my invention and set forth its merits, what I claim and desire to secure by Letters Patent is—

45 1. A heater formed of a plurality of hollow sections, each section being provided with abutting projections upon its sides, said projections decreasing in size from the bottom upwardly.

50 2. A heater formed of a plurality of hollow water sections, each section having its side walls corrugated to form staggered

arranged projections, the projections of one section registering with the projections of the adjacent section.

55

3. A heater comprising a plurality of rectangular hollow water sections, the side walls of each water section being corrugated to form staggered arranged oval-shaped projections, the projections terminating short of each edge of said sections.

4. A water section for a heater comprising a rectangular casing having its sides corrugated to form a plurality of staggered arranged oval shaped projections terminating short of each edge to form a water column the full width of each section at each edge.

65

5. A water section for heaters comprising a rectangular casing having its side walls corrugated to form a plurality of different sized projections terminating short of each edge.

6. A heater formed of one or more water sections having registering hollow projections.

75

7. A heater formed of one or more water sections having registering hollow projections decreasing in size from the bottom upwardly.

80

8. A heater for a steam or hot water system formed of a plurality of sections having registering projections, each section being provided with an independent heater, and headers in vertical alinement for feeding water to said sections and for receiving water or steam delivered from said sections.

9. In a water heater, a plurality of abutting water sections, a sectional base for supporting said water sections, a burner arranged in said base under each of said sections, each section being provided with an inlet and a discharge port, a smoke box arranged over said sections, the side walls of said sections being provided with staggered arranged registering projections of different sizes.

90

In testimony whereof I affix my signature in presence of two witnesses.

WILLIAM A. WIEDEBUSCH.
